WITNESS:

W. B. Davis, INVENTOR
BY *Victor J. Evans*
ATTORNEY

UNITED STATES PATENT OFFICE.

WILLARD B. DAVIS, OF MARIETTA, OHIO.

COLLAR BUTTON.

Application filed August 8, 1924. Serial No. 730,933.

To all whom it may concern:

Be it known that I, WILLARD B. DAVIS, a citizen of the United States, residing at Marietta, in the county of Washington and 5 State of Ohio, have invented new and useful Improvements in Collar Buttons, of which the following is a specification.

The object of my said invention is the provision of a peculiar and advantageous 10 collar button adapted to be expeditiously and easily inserted through the button holes of a neck band and collar and then manipulated to a slight extent so as to fasten it in position and preclude its casual displacement.

To the attainment of the foregoing, the invention consists in the improvement as hereinafter described and definitely claimed.

In the accompanying drawings, forming 20 part of this specification:—

Figure 1 is a view showing a collar and my novel button properly arranged relative thereto, and making clear the fact that the head of the button is of greater length than 25 width and is adapted when properly manipulated to stand at a right angle to the button holes of a collar and neck band.

Figure 2 is an enlarged elevation of my novel collar button per se.

30 Figure 3 is a transverse section taken in the plane indicated by the line 3—3 of Figure 2.

Figure 4 is a view of sectional character 35 showing one of the shank jaws of the collar button removed.

Figure 5 is a transverse section taken on the line 5—5 of Figure 4.

Similar numerals of reference designate 40 corresponding parts in all of the views of the drawings.

The collar 1 is provided with button holes 2 and is otherwise of the conventional construction.

45 My novel collar button is formed of any material or materials compatible with its purpose and comprises among other elements a head 3 which is preferably of the configuration illustrated though it may be of any other appropriate configuration provided it is of a greater length than width 50 as is clearly brought out in Figure 1.

Integral with or otherwise fixed to the head 3 is a stem 4, the portion 4^a of the stem adjacent to the head 3 being of angular

cross-section and being tapered to about the 55 point 6 in Figure 4, and the remainder of the stem being of circular cross-section as clearly brought out in Figures 4 and 5 so as to permit of ready turning of the stem about its axis. The rear end of the stem 4 60 is upset or is otherwise provided with an enlargement designated by 7.

In addition to the head 3 and the stem 4 characterized as described, my novel collar button comprises a base 8 and a shank 9, 65 the said shank 9 being split as designated by 10 from the forward end of the shank to about the point 11 shown in Figure 4, and the inner sides of the resilient jaws formed by the said split being partly of angular 70 form in cross-section and tapered to accommodate the stem portion 4^a, and the base 8 and the rear portion of the jaws of the shank being provided with a circular bore 12 for the reception of the circular portion of the 75 stem 4.

In assembling the parts of my novel button, the stem is inserted through the body formed by the base 8 and its shank and is then upset as designated by 7 or is otherwise 80 provided with an enlargement to retain it in the body and so that the head 3 bears snugly against the forward end of the shank.

In virtue of the construction of my novel button it will be manifest that the head 3 85 can be passed with great facility through the neck band hole and the buttonholes of a collar and then by the application of a little stress the head 3 can be turned to a position at right angles to the buttonholes with the 90 result that displacement of the collar button is precluded. When the head 3 is turned as stated it will be manifest that the shank jaws will give, and then will spring inwardly so as to strongly though yieldingly hold the 95 head 3 in position at right angles to the buttonholes. It will also be appreciated that when it is desired to remove the button it is simply necessary to again apply a little stress to the head 3 and turn the same back 100 to a position in coincidence with the buttonholes when the head 3 may be readily withdrawn through the buttonholes.

It will also be gathered from the foregoing that the cross-sectional shape of the shank 105 of my novel button is such that the said shank is held against turning in the buttonholes with the result that there is no liability

of the button body turning incident to the described turning of the head 3 and its stem 4.

Notwithstanding the practical advantages 5 possessed by my novel button it will be apparent that the button is susceptible of being readily manufactured, is adapted to be made in the general shape of an ordinary button, and is calculated notwithstanding its adjust- 10 able capacity to withstand the usage to which collar buttons and the like are ordinarily subjected.

I have specifically described the preferred embodiment of my invention in order to im- 15 part an exact understanding of the said em- bodiment, though I do not desire to be un- derstood as confining myself to all of the de- tails of my disclosure, the scope of my in- vention being defined by my appended claim 20 within which changes may be made without departing from my invention.

Having described my invention, what I claim and desire to secure by Letters-Pat- ent, is:—

A button having a base and a split shank 25 forming resilient jaws the interiors of which are of angular cross-section, in combination with a head of greater length than width opposed to the end of the shank, and a stem fixed with respect to said head and having 30 a portion of angular cross-section disposed between said jaws and also having an en- largement at its rear end opposed to the base; the said shank being of greater length than width in cross-section, and the angular 35 portion of the stem and the corresponding portions of the shank jaws being rearwardly tapered, and the rear portion of the stem be- ing of circular cross-section.

In testimony whereof I affix my signature.

WILLARD B. DAVIS.
